UNITED STATES PATENT OFFICE.

EMIL BALKE, OF CHARLOTTENBURG, GERMANY, ASSIGNEE TO SIEMENS & HALSEY,
A. G., OF BERLIN, GERMANY, A CORPORATION OF GERMANY.

APPARATUS FOR ELECTROLYZING LIQUIDS.

1,051,060.

Specification of Letters Patent. Patented Jan. 21, 1918.

Application filed September 24, 1912. Serial No. 722,044.

To all whom it may concern:

Be it known that I, EMIL BALKE, a citizen of the Empire of Germany, and residing at Charlottenburg, near Berlin, Germany, have 5 invented certain new and useful Improvements in Apparatus for Electrolyzing Liquids, of which the following is a specification.

My invention relates generally to an apparatus for electrolyzing liquids, especially aqueous solutions, and particularly to the manufacture of chlorid of lime from brine.

The apparatus comprises a vessel or tank subdivided by partitions of non-conducting material into a number of compartments, the tank itself being composed of stoneware, cement, sandstone or similar material. In known forms of apparatus of this kind the intermediate electrodes serving simultaneously for both poles usually either passed through the partitions or each of them formed a partition. The two last electrodes were provided with terminals for the incoming and outgoing current-leads. In such apparatus the production of the materials required involved difficulty, firstly, inasmuch as the electrodes were fixed, and consequently when the voltage was constant the current could be varied only within narrow 20 limits, and, secondly, inasmuch as substantially only one predetermined voltage could be employed.

A primary object of my invention is to obviate these drawbacks. To this end, I 35 provide the electrodes, which may be of circular, elliptical or rectangular section, and may therefore be formed as rods or plates, with a slot so that they can be mounted on the transverse walls or partitions 40 of the tank. In consequence of this simple mode of attachment the most diverse changes in the apparatus can be readily made. For example, the current can be varied by mounting a larger or smaller number of electrodes on each partition, it being possible in this manner to increase the current to double or treble its minimum value. 45 In addition, the apparatus can be adjusted to suit the voltage prevailing for the time being in the system and to meet a drop of voltage in the same, such adjustments being made either by removing one or both the terminal electrodes connected to the leads to another partition and thereby cutting one 50 or more cells into or out of circuit, or by

adding terminal electrodes to the middle of the apparatus, whereby voltages differing from the normal voltage by one half can be advantageously employed. All these changes can be made in the simplest manner 60 during working.

Several illustrative embodiments of my invention are represented by way of example in the accompanying drawings, wherein:

Figures 1, 2 and 3 are vertical longitudinal section, cross-section, and top plan view partly in section, respectively, showing an electrolytic tank fitted with one form of rod-shaped electrodes according to my invention; Fig. 4 is a top plan view showing a similar apparatus, but having rod-shaped electrodes arranged in a special manner, and Fig. 5 is a like view of a tank fitted with plate-shaped electrodes; Figs. 6 and 6^a are 75 end and side elevation, respectively, showing one form of my improved rod-shaped intermediate electrodes, enlarged; Figs. 7 and 7^a are like views, respectively, showing a rod-shaped terminal electrode of like 80 form; Figs. 8 and 8^a, and Figs. 9 and 9^a are like views, respectively, showing various forms of improved plate-shaped intermediate electrodes; Figs. 10 and 10^a are cross-section and side elevation, respectively, 85 showing another form of improved plate-shaped intermediate electrode; and Fig. 11 is a top plan view showing how several electrolytic tanks may be combined to form a single plant. 90

Referring first to Figs. 1 to 3, an oblong, rectangular tank or container 1 of earthenware or one of the above mentioned materials is divided into a number of compartments or cells 3, 3', 3'' by partitions 2 of 95 insulating material, e. g. glass, which are first loosely inserted in the tank and then cemented. On these partitions are mounted the electrodes 6 and 7, each having a slot 4, as clearly shown in Figs. 6, 6^a and 7, 7^a, two 100 electrodes being placed on each partition. The electrodes 7 on the first and last of these partitions have terminals 5 to which the leads are attached.

The electrolyte enters the tank through 105 the short pipe 8 and passes into the cell 3. Thence it flows through a small opening 9 in the first partition 2 into the next cell 3', and from the latter into the third cell 3'' by way of a second opening 9 at the side 110

of the tank opposite the first opening, and so on until it finally leaves the tank through a second short pipe 10.

The electrodes 6 are made of carbon, graphite or the like and serve as so-called bipolar intermediate electrodes, *i. e.* one limb of each electrode is an anode in one cell, and the other limb is a cathode in the next cell.

10 In the arrangement shown in Fig. 4 the partitions are considerably closer to one another, and the electrodes are so placed on these partitions that when the liquid passes from one opening 9 to the others, *i. e.* between the partitions 2, it must take a zig-zag course, and consequently becomes properly mixed and is more intensively acted upon by the current. This example shows how the apparatus can be adjusted to suit a 20 lower voltage. The end electrodes 7 are now placed on the last partitions but one, the end partitions 2' being unoccupied, and additional terminal electrodes 7 are placed on one of the middle partitions so that current 25 flows from the middle toward both ends of the tank.

Fig. 5 shows an electrolytic tank having plate-like electrodes 6' and 7', of the form shown in Figs. 8, 8^a. The electrode 6' shown in Figs. 8, 8^a consists of a single piece of graphite or carbon, while each of the electrodes 6'' and 6''' shown in Figs. 9, 9^a and 10, 10^a, respectively, is made of three parts, the middle part being so much shorter than 35 the others that the slot 4 is formed. The middle part 12 is either formed as a wedge of dove-tail section, or it has projections 13 of the same form (Fig. 9^a), which carry the outer plates 14, or it is connected to the latter by means of graphite screws 15 (Figs. 40 10, 10^a).

Lastly, Fig. 11 shows a plant in which two electrolytic tanks of the type illustrated in Fig. 5 are connected in line with one another, there being arranged between them a 45 cooling apparatus comprising a vessel 17 through which the liquid from the first tank passes, and is cooled therein by means of a cooling worm 18 or the like, before it passes 50 into the second electrolytic tank.

I claim:

1. In electrolytic apparatus of the type described, the combination of a vessel divided by partitions into compartments, each partition having an opening through which liquid to be electrolyzed can flow from one compartment to another, slotted electrodes mounted on said partitions by means of their slots, and terminals provided on some of the 55 electrodes.

2. In electrolytic apparatus of the type described, the combination of a tank divided by partitions into compartments, each partition having an opening through which 60 liquid to be electrolyzed can flow from one

compartment to another, a plurality of slotted electrodes mounted on each of said partitions by means of their slots, and terminals provided on some of the electrodes.

3. In electrolytic apparatus of the type described, the combination of a vessel divided by partitions into compartments, each partition having an opening through which liquid to be electrolyzed can flow from one compartment to another, slotted electrodes mounted on said partitions by means of their slots, and terminals provided on the outer electrodes at each end of the vessel. 75

4. In electrolytic apparatus of the type described, the combination of a vessel divided by partitions into compartments, each partition having an opening through which liquid to be electrolyzed can flow from one compartment to another, slotted electrodes mounted on said partitions by means of their slots, and terminals provided on the outer electrodes at each end of the vessel and on one of the inner electrodes. 85

5. In electrolytic apparatus of the type described, the combination of a vessel divided by partitions into compartments, each partition having an opening through which liquid to be electrolyzed can pass from one compartment to another, a plurality of slotted electrodes mounted on each of said partitions by means of their slots, and terminals provided on the outer electrodes at each end of the vessel and on some of the inner electrodes. 90

6. In electrolytic apparatus of the type described, the combination of a vessel divided by partitions into compartments, the alternate ends of the partitions having a small opening for causing liquid to be electrolyzed to flow in opposite directions in two adjacent compartments, slotted electrodes mounted on said partitions by means of their slots, and terminals provided on some of the electrodes. 100

7. In electrolytic apparatus of the type described, the combination of a vessel divided by partitions into compartments, each partition having an opening through which liquid to be electrolyzed can flow from one compartment to another, electrodes each consisting of three plates, the outer of which project beyond the middle one and thereby form a slot, mounted on the partitions by means of their slots, and terminals provided on some of the electrodes. 110

8. In electrolytic apparatus of the type described, the combination of a plurality of vessels each divided by partitions into compartments, and provided with openings in the partitions through which liquid to be electrolyzed can flow from one compartment into another, slotted electrodes mounted on each partition by means of their slots, terminals mounted on some of the electrodes, and means connecting the vessels together. 115 120 125 130

9. In electrolytic apparatus of the type described, the combination of a plurality of vessels each divided by partitions into compartments, and provided with openings in the partitions through which liquid to be electrolyzed can flow from one compartment to another, slotted electrodes mounted on each partition by means of their slots, terminals mounted on some of the electrodes,

and a cooling device interposed between each of two vessels.

In testimony whereof I have signed my name to this specification in the presence of two witnesses.

EMIL BALKE.
